COMBINATION EXHIBITION HALL AND PLANETARIUM

Bruce A. Tully, Westfield, N.J., assignor to Theodore J. Kauffeld, New York, N.Y.

Filed Feb. 1, 1961, Ser. No. 63,791

Term of patent 14 years

(Cl. D13—1)

I claim:

The ornamental design for a combination exhibition hall and planetarium, substantially as shown.
